UNITED STATES PATENT OFFICE.

ARTHUR G. SLOCUM, OF ENSIGN, KANSAS.

VAPORIZING OIL BURNER.

Application filed January 14, 1925. Serial No. 2,318.

To all whom it may concern:

Be it known that I, ARTHUR G. SLOCUM, a citizen of the United States, residing at Ensign, in the county of Gray and State of 5 Kansas, have invented certain new and useful Improvements in Vaporizing Oil Burners, of which the following is a specification.

This invention relates to a vaporizing oil 10 burner, and particularly to a construction wherein the vapor is fed to a burner chamber in which equalization of pressure is secured before ignition and a consequent even jet produced at the burner orifice. In burners of this character the vaporized fuel is 15 generally fed directly to the burner by a conduit and this results in a projected jet of flame of varying intensity depending upon the degree of heat applied to the vaporizing 20 chamber. A more desirable heating effect is secured by the use of a number of burner orifices from which the flame jets are projected by an even pressure due to the use of an equalizing chamber in the burner and a 25 plurality of connections between said chamber and the vaporizer. In order to secure the most intense heating these connections are preferably disposed at the outer periphery of the vaporizing chamber so that 30 in the use of an annular burner the heat is directly applied to the connections as well as to the chamber and a complete vaporization of the fuel thereby effected.

It is also desirable to provide an enlarged 35 heating chamber in the feed connection to the vaporizer through which the liquid fuel passes so that it is preliminarily heated and delivered over a wider area, thus avoiding any jet effect in projecting the liquid into a 40 the vaporizing chamber and resulting in a more rapid conversion of the liquid into its fluid form suitable for the burner.

The invention has for an object to provide a novel and improved construction of 45 burner provided with jet orifices and an equalizing chamber communicating with a vapor chamber at a plurality of points so that the feed from the vaporizer is distributed throughout the burner.

Another object of the invention is to provide an annular form of burner having a 50 vaporizing chamber supported above the same with a central feed thereto and a plurality of connections from the vaporizer to the burner disposed peripherally of the associated members.

A further object of the invention is to provide a separable structure comprising a priming trough having a burner base supported thereon, and a vaporizing chamber 60 having dependent therefrom a burner head provided with a plurality of orifices and peripherally disposed connections with the vaporizing chamber.

Other and further objects and advantages 65 of the invention will be herein after set forth and the novel features thereof defined by the appended claims.

In the drawings:

Figure 1 is a perspective of the invention 70 applied;

Figure 2 is a vertical section there 75 through;

Figure 3 is a section on the line 3—3 of 80 Figure 2; and

Figure 4 is a detail section on the line 85 4—4 of Figure 3.

Like numerals designate corresponding 90 parts throughout the several figures of the drawing.

The burner 10 may be of any desired size or configuration but for the purposes of the present invention is preferably circular or annular and comprises a base 11 having depending supporting legs 12 disposed at suitable positions and adapted to rest within a channel 12^a upon the bottom of the priming trough 13. This trough is of an annular form and the inner wall 14 thereof forms an air passage at the center of the burner 95 while the base of the trough rests upon a suitable support 15 having an aperture 16 communicating with such air passage. The trough may also be provided with an overflow pipe shown at 17 extending upward 100 from the bottom thereof to determine the level of fuel therein for starting the burner.

The burner base 11 being of trough-shape 105 provides an equalizing chamber 18 and the burner top 10 is adapted to seat with a tight 110 or ground joint upon the walls of the base as indicated at 19. This top is also formed with a depending portion 20 which seats within the chamber 18 and prevents lateral displacement of the top. The burner orifices 21 extend through this depending flange and are distributed at any desired intervals so as to secure an even heating effect upon the vaporizing chamber 22 which is supported above the burner. This support may be effected by various means, for instance, the conducting pipes 23 a plurality of which are

disposed at intervals between the vaporizer and burner top. The upper portion of the vaporizing chamber 22 may be formed as a flat surface 24 and thereby adapted to receive any suitable receptacle or object to be heated while the side walls 25 thereof are inclined inwardly and downwardly and merged into a bottom wall 26 which is curved outwardly from the center of the chamber so as to present a convex inner face. The outer face of this bottom wall tends to collect and trap the heat so that it is retained in contact therewith for a material period. The pipe connections 23 are disposed peripherally of the vaporizer and are slightly raised above the bottom thereof as shown at 27 so as to provide a shallow recess between the inlet for liquid fuel and the vapor delivery which will only hold sufficient liquid to be quickly vaporized.

The central portion of the bottom wall 26 is formed with a connecting collar 28 in which a centrally disposed feed pipe 29 is mounted and at its lower end connected by a reducing coupling 30 in the oil or fuel feed 31. The pipe 29 forms a heating chamber for preliminarily heating the liquid fuel before its introduction into the vaporizer so as to prevent the collection of any material quantity of liquid in the vaporizing chamber. For this purpose the member 29 is formed of materially greater diameter or area than the fuel feed pipe 31 leading thereto.

Combined with the burner I have provided a soot scraper comprising a collar 32 rotatably mounted upon the feed 29 and having radiating arms 33 disposed to traverse the burner intermediate the pipes 23 and remove collected soot therefrom. One of these arms may be extended as at 34 to provide an operating handle.

In the operation of the burner the liquid fuel is fed through the central heating pipe 29 and thereby partially vaporized before its admittance into the vaporizing chamber at the central portion thereof and the vapor is delivered from the periphery of this chamber through a series of connectors with the equalizing chamber within the burner so that the jets are provided with an even pressure of feed and the most efficient heating action secured through the central feed of air to the point of ignition. The construction presents a simple and economically manufactured form in which the parts can be readily separated for cleansing purposes as by disconnection from the feed pipe the vaporizing chamber and the burner top can be completely removed from the base so that these parts may be readily cleansed from any carbon or other collection therein. The scraper provides for cleaning the outer face of the burner while in use, by a simple movement of one of the arms. In the pre-

liminary lighting of the burner fuel is supplied to the priming trough and the burner supported therein by its legs to secure a draft until sufficient heat is established to start the vaporizing action which is automatically continued as long as the burner is in use. These legs seated in a groove also prevent any lateral displacement of the burner. The provision of a central air feed causes an upward draft against the under face of the vaporizing chamber and materially assists in the heating thereof as the burner flame is thereby deflected in the passage of the air.

While the details of construction have been specifically shown and described, the invention is not confined thereto as changes and alterations may be made without departing from the spirit thereof as defined by the appended claims.

Having thus described my invention, what I desire to secure by Letters Patent is:

1. In a vaporizing burner, an apertured annular burner cover, a vaporizing chamber supported above the same and having a central feed connection, a plurality of connections from the periphery of said chamber to said cover, a trough, and a base for said burner cover separable therefrom and provided with supports resting upon the base of said trough to space the burner therefrom.

2. In a vaporizing burner, an annular burner member, a vaporizing chamber supported above the same and having a central feed connection, a plurality of short straight connections from the periphery of said chamber at its base to said burner, a base for said burner separable therefrom and provided with supporting legs, and an annular priming trough having a channel within which said legs are disposed.

3. In a vaporizing burner, a base member provided with an equalizing chamber, a cover therefor having a plurality of burner orifices, a vaporizing chamber supported above the burner, a plurality of connections from the top of said cover to said equalizing chamber, an enlarged feed connection centrally of the vaporizing chamber, and an annular supporting trough having a central air feed surrounding said feed connection and terminating beneath the burner.

4. In a vaporizing burner, a burner member comprising an annular base provided with depending supporting means, a separable burner top provided with orifices and a central portion disposed within said base with a shoulder resting upon the side walls thereof, and conduits extending from the vaporizer through the cover for feeding a vaporized fuel at a plurality of points to the base of said burner.

5. In a vaporizing burner, an annular burner having orifices in its upper face, a

superposed vaporizing chamber, a feed pipe thereto centrally of the burner, conduits from said chamber to said burner, a collar movably mounted upon the feed pipe, and a horizontal scraper arm therefrom disposed to traverse the upper face of the burner.

5 6. In a vaporizing burner, an annular burner, a superposed vaporizing chamber, a feed pipe thereto centrally of the burner,

conduits from said chamber to said burner, 10 a collar movably mounted upon the feed pipe, and a plurality of radiating scraper arms disposed intermediate said conduits to engage the burner face.

In testimony whereof I affix my signature.

ARTHUR G. SLOCUM.
